UNITED STATES PATENT OFFICE

LEOPOLD ROTHMUND, OF STUTTGART, GERMANY

SLUICE OR LOCK

Application filed October 23, 1929, Serial No. 401,773, and in Germany November 1, 1928.

My invention relates to sluices or locks and more particularly to the type of lock having a floating dock-like trough with a ballast chamber.

5 It is an object of my invention to improve a lock of this type.

To this end I combine with the floating trough a floating reservoir having a ballast chamber of its own, and I provide means for 10 connecting the two ballast chambers in such wise that ballast water can pass from one to the other as the circumstances require.

In a modified form, which offers particular advantages, the floating reservoir is replaced 15 by a second dock-like trough similar to or identical, as far as its design is concerned, with the other trough, and affording a means for simultaneously passing two vessels or rows of vessels through the lock.

20 The trough or troughs which take up the vessels, float in a basin which is connected to head water and separated from tail water by a lock bay.

The new lock is operated exclusively by 25 means of the ballast water which is made to flow from the floating trough to the floating reservoir or the second trough, if such is provided, the ballast water providing that the trough is submerged when the vessel is moving downstream, and raised when it is moving upstream, without any expense of power except that required for generating the head which causes the ballast water to flow, and for overcoming the resistances to the movement 30 of the trough and reservoir.

Communication is established between the floating trough and the floating reservoir or the second floating trough across a partition or middle float which is loaded with ballast 40 so as to seat itself, if desired, on the bottom of the lock chamber. It might however also be replaced by a fixed non-floating partition. This middle float has a chamber affording a passage for the ballast water from one to the other trough or reservoir. These latter are arranged to slide vertically in contact with one or the other side wall of the middle float, being guided on these side walls by means of slides fixed to them which are so proportioned 45 as to close the passage chamber in the middle

float, no matter in what position the trough or reservoir may be, an opening in the slide allowing however ballast water to pass through from one ballast chamber to the other across the middle float and the slides. 55

Means are provided in the ballast chamber for controlling the flow of the water and means are further provided for starting the floats moving in vertical direction.

In the drawings affixed to this specification 60 and forming part thereof, various embodiments of my invention are illustrated diagrammatically by way of example.

In the drawings

Fig. 1 is a cross-section of a lock chamber 65 with an open trough in upper and a floating reservoir in lower end position,

Fig. 2 is a similar view showing the parts in reversed positions,

Figs. 3 and 4 are similar views of a lock 70 chamber having a covered (closed-in) trough and a reservoir,

Figs. 5 and 6 illustrate a lock with a modified form of the trough shown in Figs. 3 and 4, 75

Fig. 7 illustrates a lock chamber provided with two floating troughs, one acting as ballast reservoir for the other,

Fig. 8 is an elevation of the float viewed in the direction of the arrows in Figs. 1 and 10, 80 and

Figs. 9 and 10 are sections on lines IX-IX and X-X in Fig. 8.

Referring now to the drawings, and first to Figs. 1 and 2, 7 is the lock basin and 6 is 85 the water level therein, 1 is the floating trough adapted to be closed at either end by gates (not shown) of some suitable type and only partly filled with water for the reception of a vessel (not shown), the height of its walls being such, that they enclose a large air-filled space which acts as a water displacing chamber. 2 is the floating reservoir, equally formed with an air-filled displacing chamber 17, and 3 is the middle float. Slides 4, 5 90 are arranged on either side of the middle float for vertical displacement on the side walls thereof, suitable means (not shown) being provided for guiding the slides on the float. Suitable means (not shown) such as a 95 100

winch, may be provided on the middle float 3 for raising and lowering the slides.

The middle float 3 is formed with a central chamber 8 open on both sides through which the ballast water may pass from the floating trough 1 to the floating reservoir 2. The middle float 3 is formed with closed air chambers 9 and 10 above and below the passage 8. Suitable means, such as screw spindles, may be provided for adjusting the middle float relative to the foundation 11 so that the vertical position of the float can be varied in accordance with the variations of the head and tail water levels.

Suitable packing frames 12 and 13 of a well-known kind are provided on either side in suitable recesses of the middle float 3 so as to make a tight fit between the openings in the middle float and the floating trough and reservoir, respectively.

The floating trough is mounted on a ballast chamber 14 and is formed with high walls 51 and with a closed air chamber 15 which together with the upper air-filled and water displacing portion 50 of the trough proper serves for regulating the buoyancy of the trough. Similarly the reservoir 2 is provided with a ballast chamber 16 and the air-filled displacing member 17. 43, 43 and 44 are overflow pipes or passages in the ballast chambers 14 and 16, respectively. Vents, such as indicated at 140 and 160 in Fig. 1, are provided on the ballast chambers of this and all other modifications described further below, these vents serving to establish communication of the air space in these chambers with the atmosphere and to allow air to escape and enter, as the water rises and falls therein, respectively. In head water position the displacing chamber formed in the top part of said trough is fully above, the displacing chamber of the reservoir below the water level in the lock basin. The two ballast chambers are below this level both in head and in tail water position.

The ballast chambers of the trough 1 and the reservoir 2 are formed with channels 14a and 16a respectively extending below the bottom of and communicating with said chambers, these channels ending in, openings 18 and 19, respectively, in the side walls adjoining the middle float 3 and near the bottom thereof. These openings register permanently with the chamber 8 in the middle float and suitable packing frames 20, 21 are provided to secure a tight fit. A pair of sliding gates 22 and 23 is provided for controlling the passage 18 and similar gates 24 and 25 control the passage 19. The inner gates 23 and 25, which are the principal gates, may be provided with automatic means (not shown) for lowering them whenever the velocity of the flow of the water should become excessive. The outer gates 22, 24 are provided for the case of an emergency.

In Figs. 8, 9 and 10, the packing and guiding means are shown more specifically, Fig. 8 being an elevation of the float 3 with the packings arranged thereon, viewed in the direction of the arrows in Figs. 1 and 10. The inner part 26 surrounding the chamber 8 comprises a holder in which a packing strip 27 is fitted to slide. This strip is held applied against the slide 4 by means of pistons 28 arranged in cylinders 29. A similar packing 12 is provided for the slide 4.

The rotatably mounted packing rollers 30, pairs of which are provided above and below chamber 8 on both sides of the float 3 for cooperation with the two slides 4 and 5, respectively, are lined with rubber and held applied against the corresponding slide (4 or 5) by a piston 31 movable in a cylinder 32 mounted on the middle float 3, the piston rod carrying a smaller roller 33 for forcing the packing roller 30 into contact with the slide. 34 is a packing strip secured on the horizontal wall of the recess, and held in contact with roller 30. The walls 35 of the middle float 3 are provided with guide wheels 36 supported in a frame 37 which moves on rails 38 of the slide. 39 is a packing strip which is secured to the float 3 along the walls 35, 35 and recessed at 40 to form a labyrinth packing which is supplemented by a packing strip 27 held applied against the slide (4 or 5) by pistons 28 as described with reference to Fig. 9.

The operation of the new lock is as follows:

The position of the trough 1 with respect to the level of the body of water 6, in which it floats, is regulated by the water ballast in the chamber 14 and the relative position of the trough 1 and reservoir 3 is regulated by causing water from the chamber 14 of the trough to flow into the ballast chamber 16 of the reservoir 2, or vice versa. With the trough 1 in its upper end position the reservoir 2 is submerged, the water level in chamber 14 of the trough being flush with the discharge pipes 43 so that this chamber is now empty, the chamber 16 of the reservoir 2 being filled altogether. The inner gate 23 of ballast chamber 14 is closed, while in the reservoir chamber 16 the inner gate 25 is open, the outer slides being open also, the slide 4 being lowered, the slide 5 raised to connect the passages 18 and 19 of the channels 14a and 16a, respectively, with the passage 8 in the middle float 3.

In the position illustrated in Fig. 1, with the trough 1 in its upper position and the reservoir 2 submerged the total weight of the trough including the water in it equals the buoyancy of the trough with the water discharged from the chamber 14. Equally, the weight of the reservoir and the weight of the water in the chamber 16 must be equal to the buoyancy of the reservoir when totally submerged.

In Fig. 2, the relative position of the trough and the reservoir is reversed, the reservoir 2 floating, its ballast chamber 16 being emptied, and the trough 1 being submerged and its ballast chamber 14 filled. In this position the inner gate 25 in the reservoir 2 is closed, while in the trough 1 both gates 22 and 23 are open. It will be understood that whenever the relative position of the trough and the reservoir is reversed, a certain quantity of water will flow from chamber 14 into chamber 16 and vice versa. This shifted body of water is equal to the water displaced by the trough 1. The capacity of the water spaces in the chambers 14 and 16 must be equal to the shifted body of water and the height of the air spaces in both chambers must be the same and must be equal to the distance between the two end positions of the trough. A further condition is that the ballast water chambers should be so designed that the cross-sectional areas of their water levels are equal at all relative positions at which the trough 1 and the reservoir 2 are at equilibrium, and equal also to the cross-sectional area of the water displaced by the trough in the lock chamber in which it floats. It follows from these conditions that the height of the ballast water chambers in the trough and the reservoir must be equal, that their capacities must be equal and that the cross-sectional area of the level of the volume of water displaced by the trough must be equal to that displaced by the reservoir and vice versa.

By slightly varying the vertical position of the trough 1, the reservoir 2 or both, for instance by lowering slightly the trough from its upper end position with the vessel therein designed for down-stream movement a flow of water will be set up from chamber 16 to chamber 14 so that the reservoir 2 will rise through the same distance for which the trough is lowered, and this will go on until the trough is completely submerged. While this occurs, all forces, with the only exception of the force required for imparting acceleration to the trough, are balanced and the level of the body of water 7 will be constant. When the trough has reached its lowermost position, the vessel may pass down-stream without the reservoir being affected thereby. With a vessel moving upstream the sequence of operations is reversed. The slides 4, 5 are displaced together with the trough and reservoir. When the trough 1 has been completely submerged its ballast chamber 14 is completely filled without requiring any closure and the trough (Figs. 4, 6 and 7) may now move further downwardly. On the other hand, when the trough is completely submerged, the gate 25 in the reservoir 2 is closed. When the trough shall be submerged further, the packing frame 20 is withdrawn from contact with the slide 5 by automatic means, either pneu-

matic or hydraulic. When the trough starts again on its upward movement, the packing 20 is automatically returned into operative position. This independent movement of the trough is very important for a vessel moving down-stream, because thus the vessel may move at any desired depth. The chamber 14 of the dock remains in connection with the body of water 6. In this manner the volume of shifted balance water is regulated automatically during every operation of the lock. Any water that remains in the chambers 14 or 16 is discharged freely by the pipes 43 and 44, respectively, while any shortage of water is made up from the bodies of water 80 in the lock chamber.

Referring to Figs. 3 and 4, the trough 45, which corresponds to the trough 1, is closed on top but otherwise the construction of the floats with their displacing and ballast chambers, is the same as described with reference to Figs. 1 and 2.

In Figs. 5 and 6 the ballast chamber 14 of the previously described modifications is here replaced by a chamber 46 of substantially the same width as the trough 45. Obviously in this case only a single pipe 47 is required in the chamber 46.

In Fig. 7, the floating reservoir 2 in Fig. 1 is replaced by a second trough 48 equaling in all respects the trough 49, each trough acting as a ballast reservoir for the other and both troughs being utilizable alternately in the same manner.

In the claims the term reservoir is intended to include a second trough as shown in Fig. 7.

I wish it to be understood that I do not desire to be limited to the exact details of construction shown and described for obvious modifications will occur to a person skilled in the art.

I claim:

1. In a lock in combination, a water-filled basin, a high-walled floating trough, a body of water in the bottom portion of said trough, the top portion forming a displacing chamber, a ballast chamber below said trough, a floating reservoir alongside of said trough, a displacing chamber and a ballast chamber in said reservoir, the displacing chamber of said trough being, in head water position, above the water level, the displacing chamber of said reservoir below the water level in said basin.
2. In a lock in combination, a water-filled basin, a high-walled floating trough, a body of water in the bottom portion of said trough, the top portion forming a displacing chamber, a ballast chamber below said trough, a floating reservoir alongside of said trough, a displacing chamber and a ballast chamber in said reservoir, the displacing chamber of said trough being, in head water position, above the water level, the displacing chamber of said reservoir below the water level, in said basin.

ber of said reservoir below the water level in said basin, and means for passing ballast water from one ballast chamber to the other.

3. In a lock in combination, a water-filled 5 basin, a high-walled floating trough, a body of water in the bottom portion of said trough, the top portion forming a displacing chamber, a ballast chamber below said trough, a floating reservoir alongside of said trough, 10 a displacing chamber and a ballast chamber in said reservoir, the displacing chamber of said trough being, in head water position, above the water level, the displacing chamber of said reservoir below the water level in 15 said basin, and means between said trough and said reservoir for passing ballast water from one ballast chamber to the other.

4. In a lock in combination, a water-filled 20 basin, a high-walled floating trough, a body of water in the bottom portion of said trough, the top portion forming a displacing chamber, a ballast chamber below said trough, a floating reservoir alongside of said trough, a displacing chamber and a ballast chamber 25 in said reservoir, the displacing chamber of said trough being, in head water position, above the water level, the displacing chamber of said reservoir below the water level in said basin, and floatable means for passing 30 ballast water from one ballast chamber to the other.

5. In a lock in combination, a water-filled 35 basin, a high-walled floating trough, a body of water in the bottom portion of said trough, the top portion forming a displacing chamber, a ballast chamber below said trough, a floating reservoir alongside of said trough, a displacing chamber and a ballast chamber 40 in said reservoir, the displacing chamber of said trough being, in head water position, above the water level, the displacing chamber of said reservoir below the water level in said basin, and floatable means for passing ballast water from one ballast chamber to 45 the other, and means associated with said balance chambers for controlling the passage of water.

6. In a lock in combination, a water-filled 50 basin, a high-walled floating trough, a body of water in the bottom portion of said trough, the top portion forming a displacing chamber, a ballast chamber below said trough, a floating reservoir alongside of said trough, a displacing chamber and a ballast chamber 55 in said reservoir, the displacing chamber of said trough being, in head water position, above the water level, the displacing chamber of said reservoir below the water level in said basin, a partition between said 60 trough and said reservoir, a water passage in said partition, a slide on each side and in contact with said partition, a communication between said 65 ballast chamber and the water passage in said partition extending across said slides, and means for causing

simultaneous vertical movement of said trough and said reservoir respectively with the slide adjoining each.

7. In a lock in combination, a water-filled 70 basin, a high-walled floating trough, a body of water in the bottom portion of said trough, the top portion forming a displacing chamber, a ballast chamber below said trough, a floating reservoir alongside of said trough, a displacing chamber and a ballast chamber in 75 said reservoir, the displacing chamber of said trough being, in head water position, above the water level, the displacing chamber of said reservoir below the water level in said basin, a floatable partition between said trough and said reservoir, a water passage in 80 said partition, a slide on each side and in contact with said partition, a communication between said ballast chamber and the water passage in said partition extending across said slides, and means for causing simultaneous vertical movement of said trough and 85 said reservoir respectively with the slide adjoining each.

8. In a lock in combination, a water-filled 90 basin, a high-walled floating trough, a body of water in the bottom portion of said trough, the top portion forming a displacing chamber, a ballast chamber below said trough, a floating reservoir alongside of said trough, a displacing chamber and a ballast chamber in 95 said reservoir, the displacing chamber of said trough being, in head water position, above the water level, the displacing chamber of said reservoir below the water level in said basin, a partition between said trough and said reservoir, a water passage in said partition, a slide on each side and in contact with 100 said partition, a communication between said ballast chamber and the water passage in said partition extending across said slides, means for causing simultaneous vertical movement of said trough and said reservoir respectively with the slide adjoining each and means for packing said slides against said partition.

9. In a lock in combination, a water-filled 105 basin, a high-walled floating trough, a body of water in the bottom portion of said trough, the top portion forming a displacing chamber, a ballast chamber below said trough, a floating reservoir alongside of said trough, a displacing chamber and a ballast chamber in 110 said reservoir, the displacing chamber of said trough being, in head water position, above the water level, the displacing chamber of said reservoir below the water level in said basin, a partition between said trough and said reservoir, a water passage in said partition, a slide on each side and in contact with 115 said partition, a communication between said ballast chamber and the water passage in said partition extending across said slides, means for causing simultaneous vertical movement of said trough and said reservoir respectively with the slide adjoining each, means for pack- 120

125

130

ing said slides against said partition, and means for packing said trough and reservoir against said slides.

10. In a lock in combination a water-filled basin, a high-walled floating trough, a body of water in the bottom portion of said trough, the top portion forming a displacing chamber, a ballast chamber below said trough, a floating reservoir alongside of said trough, a displacing chamber and a ballast chamber in said reservoir, the displacing chamber of said trough being, in head water position, above the water level, the displacing chamber of said reservoir below the water level in said basin, a partition between said trough and said reservoir, a water passage in said partition, a slide on each side and in contact with said partition, a communication between said ballast chamber and the water passage in said partition extending across said slides, means for causing simultaneous vertical movement of said trough and said reservoir respectively with the slide adjoining each, means for packing said slides against said partition, and means for packing said trough and reservoir against said slides, said packing means comprising packing members and pistons arranged to move said members into and out of operative position and packing rollers movable in labyrinth-like recesses.

36 In testimony whereof I affix my signature.
LEOPOLD ROTHMUND.
